UNITED STATES PATENT OFFICE.

WILLIAM N. WINFIELD, OF DETROIT, MICHIGAN.

INDEX-LEAF.

SPECIFICATION forming part of Letters Patent No. 624,718, dated May 9, 1899.

Application filed September 15, 1898. Serial No. 691,037. (No model.)

To all whom it may concern:

Be it known that I, WILLIAM N. WINFIELD, a citizen of the United States, residing at Detroit, in the county of Wayne and State of Michigan, have invented certain new and useful Improvements in Ledgers, of which the following is a specification, reference being had therein to the accompanying drawings.

The invention relates generally to ledgers, and has particular reference to a balance-book used in connection therewith.

The invention consists in the novel construction of a balance-book leaf and the peculiar arrangement, combination, and construction of the various parts thereof, all as hereinafter shown and described.

In the drawings, Figure 1 is a perspective view of a ledger, showing my improvement attached thereto, the ledger being open and the balance-book and index being attached and likewise open as in use. Fig. 2 is an enlarged section through the outer edge of the ledger and through the balance-book and index. Fig. 3 is an end elevation of the ledger in its closed position. Fig. 4 is an enlarged plan view of the balance-book and index, showing the same open. Fig. 5 is a section through one of the leaves of the balance-book and index, showing the manner of building it up.

A is a ledger, either a regular bound book or a loose-leaf binder, as desired. In the drawings I have shown it as a loose-leaf ledger having suitable covers B and C. To one of these covers, preferably the back one, I detachably attach the balance-book and index D. This latter consists of covers E and leaves F of the construction to be hereinafter described, the covers being hinged together by the usual manner, so as to open and close the book. To one edge of one cover is flexibly connected a tongue G, as by means of the flexible strip or strap H, and this tongue G is adapted to enter a pocket I, formed at the edge of the cover.

It is not essential to my invention that the particular means of detachably connecting the balance-book and index shall be the tongue G, as any other form of detachable means may be employed, it being only essential that the book D shall be such a one as can be folded back upon the cover, so that

when the ledger is closed it will be within the covers of the ledger, as shown in Fig. 3. The pages of the book D are each ruled into at least two columns *a* and *b*, which are provided with the usual lines for writing thereon. The column *a* is intended for the name of the person, and the column *b* is ruled for figures, so that the balance of the individual may be marked thereon. In some instances I preferably subdivide the column *b* to form a column *c* for the purpose of indicating the page or sheet in the ledger in which the account is kept. The column *b* I make of such proper material so that the figures thereon may be erased at will, and this I preferably do by using some silicate preparation or a specially-prepared paper which will permit of this erasure and the easy writing thereon of figures. In making a leaf for this book I take a sheet *d* and upon the outer half of one face I place the erasing-tablet *e*, upon which is formed the column *b*. Upon the inner edge or half of the other face of this sheet I place a corresponding tablet *e*. Then in order to make the faces flush I may and preferably do place in the remaining exposed portions of the sheet *d* suitable cardboard or heavy-paper tablets *h*, as plainly shown in Fig. 5, and thus make a leaf of triple thickness, the half of each exposed surface being of specially-prepared material, so that it may be written on and the writing easily erased.

In banks and other similar places of business it is desirable to keep accurate records at all times of the balance of each individual. Therefore in posting onto the ledger the book-keeper keeps open before him the balance-book and index D, preferably at the right hand, as shown in Fig. 1, and when he finds the balance of a certain individual's account he erases the previous figures of the balance indicated opposite that individual's name in the book and places the proper balance therein. The balance in the ledger proper is made in ink, and therefore makes a permanent record, while the record on the book D of the balance is simply a temporary one for reference in the manner desired. In banks, for instance, when the bookkeeper has corrected the balance of all depositors whose balance has changed during the day he can detach the book D from his ledger and hand it to the

teller, who thus will have before him each day the proper balance of every individual, and can thus prevent the possibility of over-draft with the least possible expenditure of time on his part.

At the close of the day's business the book-keeper can attach his balance-book to the edge of his ledger again, erase the old balances, and insert the new ones for the next day's work. It is evident that inasmuch as the balances are all in a single book in convenient form they may be footed to give the total at any time with the least possible trouble.

15 The balance-book is indexed by having the names arranged therein alphabetically and provided with any suitable index therefor, such as tags or an indented alphabetical index.

20 A book of this kind has been found to be of great value to bankers and other business men who require to keep accurate balances of their customers' accounts. At night the book may be put away within the ledger in

25 the manner described by folding it, as shown in Fig. 3, so that there is no chance of mis-

placing it, and it practically takes up no extra room. Moreover, the novel means I employ for detachably securing the index to the ledger not only forms a desirable connection 30 between the two books, but a part of the securing device constitutes a cover for the front edges of the index-leaves when the index-book is in its folded position within the ledger or when said index-book is detached from the 35 ledger and filed away. This is a desirable feature, particularly in the latter case, as the index proper, which is usually formed in the front edges of the index-book, is effectively protected from dust and dirt. 40

What I claim as my invention is—

The combination in an index balance-book, of a leaf, of the tablets *e*, reinforcing the outer and inner portions of opposite sides, and the tablets *h* on the remaining portions of said 45 leaf.

In testimony whereof I affix my signature in presence of two witnesses.

WILLIAM N. WINFIELD.
